TENT PEG

Athol M. Carr-Harris, 316 Balsam Drive,
Oakville, Ontario, Canada

Filed Feb. 14, 1966, Ser. No. 1,023

Term of patent 14 years

(Cl. D88—3)

FIGURE 1 is a rear perspective view of a tent peg showing one side and the top of my new design;

FIGURE 2 is a front perspective view thereof showing the other side and bottom;

FIGURE 3 is a top elevation of said tent peg; and
FIGURE 4 is a bottom elevation thereof.

I claim:

The ornamental design for a tent peg, as shown.
